UNITED STATES PATENT OFFICE.

WILLIAM B. GOULD, OF NEW YORK, N. Y.

DESIGN FOR STAIR-ROD.

Specification forming part of Design No. 5,178, dated August 8, 1871.

To all whom it may concern:

Be it known that I, WILLIAM B. GOULD, of the city of New York, in the county and State of New York, have invented a new and Original Design for a Stair-Rod; and I do hereby declare that the following is a full, clear, and exact description thereof, which will enable others skilled in the art to make and use the same, reference being had to the accompanying drawing forming part of this specification.

Figure 1 represents a side view of my new stair-rod. Fig. 2 is an end view of the same.

Similar letters of reference indicate corresponding parts.

This invention relates to a new form of stair-rod; and consists in making the same six-sided in cross-section, as in Fig. 2, but with twisted or spiral sides, as clearly shown in Fig. 1.

I claim as my invention—

The design for a six-sided twisted stair-rod, as shown.
